UNITED STATES PATENT OFFICE.

NELSON MERRILL, OF NEW YORK, N. Y.

TRICYCLE.

SPECIFICATION forming part of Letters Patent No. 291,576, dated January 1, 1884.

Application filed May 29, 1883. (No model.)

To all whom it may concern:

Be it known that I, NELSON MERRILL, of the city, county, and State of New York, have invented a new and useful Improvement in 5 Tricycles; and I do hereby declare that the following is a full and exact description thereof, reference being had to the accompanying drawings, and to the letters of reference marked thereon, making a part of this specification.

10 My invention relates to an improvement in tricycles, and more especially to the improved tricycle for which Letters Patent of the United States were granted to me November 22, 1881, No. 249,853, but which is applicable as well to other forms of machines.

15 It consists in the combination of the pitman-rods which actuate the saddle-lever with short cranks upon an auxiliary idle-shaft, which is also formed or fitted with cranks corresponding 20 with the foot-crank upon the driving axle, so as to be, in fact, a duplicate thereof, and which is supported in suitable bearings upon the frame in front of said axle, to revolve freely in line parallel therewith, and in the combination, 25 with the wrists of the corresponding cranks on the shaft and axle, of coupling-bars carrying the pedals or serving as treads for the machine, and to connect said cranks, and so bent or arranged as to bring the weight of 30 the rider in front of the axle, and to support the operator's feet at a distance above the cranks during their entire revolution.

35 The object of this part of my invention is to obtain an increase of leverage upon each driving-crank without increasing the travel of the foot in operating the crank; to bring the foot farther forward and in a more natural and easy position when at work, the rider being seated over or in front of the axle, and to obtain 40 an effective forward thrust against the cranks as the saddle descends under the weight of the rider.

45 It consists, furthermore, in the combination of a suitable steering-gear with the lever upon which the seat is mounted, and which is pivoted meditately to the tubular standard in which the fork or post carrying the steering-wheel rotates.

50 In the accompanying drawings, Figure 1 is a side elevation of my improved tricycle with

the nearest driving-wheel removed; Fig. 2, a plan view of the same machine; Fig. 3, a plan view, illustrating a modification in the construction of the axle and its connection with the idle-shaft; and Fig. 4, a diagram illustrating the sweep of the cranks and the movement of the foot bearing upon the link connecting them.

55 A represents a light, strong, forked frame, whose two parallel horizontal arms furnish or support bearings for the axle B and for a parallel shaft, C, placed in front thereof. The forward end or reach, W, of the frame A is firmly secured to a vertical tubular standard, D, through which, as a pivotal bearing, the upper end of the fork E, carrying the front steering-wheel, F, is carried. The axle B is formed with two pedal-cranks, *a a*, disposed at an angle of one hundred and twenty degrees with each other, and outside of these with two short 60 seat-cranks, one at each end, projecting both in the same plane at an angle of one hundred and twenty degrees with the pedal-cranks, in manner as set forth in my aforesaid Letters Patent of November 22, 1881. The parallel 65 shaft C is mounted in front of the cranked axle B at a distance therefrom somewhat exceeding the length of the pedal-cranks, to rotate freely 70 in suitable bearings upon the frame. It is constructed with a series of cranks corresponding 75 in all respects with the cranks on the axle B. Pedals G G are supported immediately over the wrists of the pedal-cranks *a* on the idle-shaft C, each upon a connecting-rod, *cd*, pivoted at its front end, *c*, to the wrist of the front 80 crank, *a'*, and at its rear end, *d*, to the corresponding pedal-crank, *a*, on the axle. By means 85 of this connecting-rod *cd* the two cranks *a a'* are not only coupled together so that they shall revolve in unison, but the pedals are constantly upheld thereby above the cranks in the entire circle of their movement, and, if desired, 90 in such manner as that the foot shall project forward of and overhang the end of the crank. This overhanging of the pedal beyond and in 95 front of the wrist of the front crank operates virtually as an extension of the length of the crank as it approaches a horizontal plane in front of its shaft, furnishing additional leverage at the moment the crank is brought into 100

effective action, without, however, increasing the length of the stroke or up-and-down movement of the foot in operating it. (See diagram, Fig. 4.) The seat-cranks e e on the axle may 5 likewise be coupled with the counterpart seat-cranks e' e' on the idle-shaft by straight connecting-bars H H . The seat or saddle K of the machine is fitted directly over or somewhat in front of the axle B upon the rear end of a 10 long lever, L , which is pivoted at its front end to the upper end of an upright bar, M , Fig. 1. The lower end of the bar M is pivoted to the reach W of the frame, so that its upper end shall be free to vibrate slightly within a 15 shackle or loop, i , by which it is tied to the upper end of the standard D . The saddle K is connected to the seat-cranks e' e' by means of two rods, J J , pivoted to the saddle or its lever L , and whose lower ends are secured each 20 to one of the bars H H , or pivoted directly to one of the cranks e e . The upward movement of the reciprocating rods J J , actuated by the cranks e' e' , produce an upward movement of the seat-lever and seat, while the downward 25 movement of the seat, under the weight of the rider, actuates the cranks, and is thereby utilized in the propulsion of the machine. A sprocket-wheel, N , Fig. 2, is mounted upon a vertical spindle, which is supported and pivoted 30 in a bracket on the seat-lever L and terminates in a handle, P , within easy reach of a person seated on the saddle K . A chain is led around the sprocket-wheel N , and its ends are connected directly or by means of intermediate 35 cords or rods, Q Q , with the two ends of a handle, R , upon the upper end of the fork E , carrying the front wheel, F , so that the rotation of the wheel N , produced by manipulating the handle P , will actuate the handle R , and 40 with it the front wheel, F , to turn it in either direction. A horizontal wheel or segment may be substituted for the handle R as an equivalent device to actuate the fork E .

45 S S are brake-shoes upon the ends of a horizontal bar, S' , properly supported in brackets under the front bar of the frame A , and which is drawn to or carried from the driving-wheels F' F' by means of a compound lever, whose two arms, T T' , hinged together, are each pivoted 50 to the arms of a bracket provided therefor, and which is secured upon the reach W , as shown in Fig. 1. The lower end of the lower arm, T' , is coupled to the brake-bar S' or to a link extending thereto. The upper 55 end of the upper arm, T , is fitted with a pedal, U . By applying the pressure of the foot to said pedal U , and thereby vibrating the upper arm, T , a powerful leverage is exerted upon the lower arm, T' , and through it upon 60 the bar S , operating to draw the brake-shoes against the wheels.

65 In the modification in the construction of the machine illustrated in Fig. 3, the seat-cranks e' e' on the axle are omitted therefrom, leaving only the pedal-cranks to be connected by the rods c d with counterpart cranks on the

idle-shaft C . In such case the reciprocating seat-rods J J are pivoted directly to the wrists of seat-cranks e' e' , formed upon said idle-shaft, as shown in Fig. 3. If desired, a reverse 70 movement of the driving-wheels may be automatically prevented by means of pawls v v , pivoted to the axle, to engage ratchet-wheels x x on the hub of each wheel.

In the use of my improved tricycle, constructed as described, the weight of the rider mounted upon the saddle K is brought into constant and effective operation for the propulsion of the machine. In operating the machine, the rider, seated in the saddle immediately over or somewhat in front of the axle, places his feet upon the pedals, which are in front of the axle and of the rider's body, and within easy and natural reach of the feet at all points of their revolution. As the weight 85 of the uppermost foot is brought to bear upon its pedal, the two connected cranks are thereby made to revolve, and as the foot is carried forward and downward a leverage is exerted upon the cranks, which increases as the crank-arm approaches the horizontal. While there is this gain in leverage upon the crank, the throw or movement of the foot is not increased, the sweep of the pedal vertically and horizontally being determined by the length of the 90 crank alone, irrespective of the form or length of the coupling-bars, as is illustrated by the dotted lines in Fig. 4. So soon as pressure upon one foot has brought the crank upon which it bears beyond the line of most effective leverage, the crank under the second foot has attained a point in the revolution where it becomes most effective under the application of weight and power thereto to produce a rotation of the shaft; and when in its movement it has passed beyond the point of effective leverage, and the crank under the first foot is still rising, and hence is inoperative, the seat-cranks reach their point of effective leverage, and the weight of the rider, being 100 thereupon transferred from the pedal wholly to the seat, operates effectively upon said cranks until the first foot can be again brought effectively into play.

The location of the pedals upon the coupling-bars c d , which connect the crank upon the axle with cranks upon an idle-shaft, by means whereof the weight of the driver is thrown in front of the axle, and the connection of the seat placed over the axle, with the 110 cranks on the idle-shaft in front of the axle, which operates as a driving-shaft, by means whereof the weight of the driver, when not used effectively upon the pedals, is applied with a forward thrust against the seat-cranks, 115 serve to increase largely the efficiency of the machine, and to insure simply and practically a direct and positive application of the weight and muscular power of the rider to the cranks and wheels without any increase in the movement of the foot and legs over that required 120 in the most approved forms of bicycles and 125 130

tricycles. Moreover, by reason of the position of the pedals with relation to the saddle and the steering - handle on the saddle-bar, when the weight of the rider is thrown upon the pedals, he may grasp the handle, and, by pulling thereon as he rises from the saddle to bear upon the pedals, may lift the seat-lever, and thus exert an upward pull upon the seat-cranks, which will greatly assist in effecting a revolution of the wheels. At the same time, by straightening out his flexed arms and knees, he is enabled to exert with ease a powerful muscular force, which will be brought to bear in addition to his mere weight force, directly upon the cranks in propelling the machine. I contemplate, furthermore, aiding this up-pull with the hands in rising by means of shoulder-straps led over the shoulders of the rider, and secured at either end to the saddle or its pitman-rod, so that by slightly straightening the body as well as the legs, in making the rise in the saddle, the up-pull on the seat-lever, as well as the down-push on the cranks, will be increased or enforced, while the shoulder-straps will also afford a certain support to the rider when thus working the machine. I reserve the right to make this feature of my invention the subject-matter of a separate application for Letters Patent. The down-push of the seat in descending may also be increased by a simultaneous counter up-pull upon the cranks, with the toes of the feet against the straps secured for the purpose over the ends of the pedals. The pedal-cranks on the axle and idle-shaft may be coupled by straight bars connected to the one and the other, instead of by the bent bars *c d*, as shown, the latter being preferred in order to throw the feet more to the front, and to permit a higher adjustment of the seat, and a better alignment of the pitman-rods extending diagonally thereto from the seat-cranks.

I contemplate the use of the parallel idle-shaft formed with cranks the counterpart of the cranks upon the axle, in the construction of velocipedes adapted to carry two persons, with three cranks one hundred and twenty degrees apart, in which the middle crank is operated by the two adjacent feet of the riders bearing jointly thereon and the other two cranks by the right foot of the one and the left foot of the other.

It is evident that the power applied by the within-described devices to produce the rota-

tion of the axle of a velocipede may be employed by similar devices to drive a shaft rotating in fixed bearings for use as a motor, and I contemplate such an application of my invention.

I purpose to make hereafter the use of shoulder-straps, and also the construction of a machine to accommodate two persons, the subject-matter of separate Letters Patent, and to claim therein such devices herein described as may be novel in that connection.

I claim as my invention—

1. In a velocipede or motor, the combination, with its axle or driving-shaft, a seat mounted to vibrate vertically over the same, and an idle-shaft rotating in line parallel with the axle or driving shaft, of one or more cranks formed on said idle-shaft and coupled by pitman-rods with the vibrating seat or seat-lever, pedal-cranks also formed on said shaft at an angle of about one hundred and twenty degrees with each other and with the seat-cranks, and counterpart pedal-cranks formed on the axle or driving-shaft, and coupled by connecting-bars with the pedal-cranks on the idle-shaft, substantially in the manner and for the purpose herein set forth.

2. The combination, with the rotating fork or spindle carrying the steering-wheel of a velocipede, a vibrating lever pivoted to the standard supporting said fork and actuated by cranks upon the axle or a counterpart idle-shaft driven thereby, and a seat fitted upon the lever to partake of its movement, of a steering wheel or handle mounted upon said lever within reach of the rider upon the seat and geared to the fork or spindle of the driving-wheel, substantially in the manner and for the purpose herein set forth.

3. The combination, in a velocipede or motor, with the counterpart pedal-cranks upon its driving-axle and auxiliary idle-shaft, of a pedal bar or bars adapted to uphold the foot of the operator above the crank of the idle-shaft during its entire revolution, and to couple said crank with the corresponding crank upon the driving-axle, substantially in the manner and for the purpose herein set forth.

In testimony whereof I have signed my name to this specification in the presence of two subscribing witnesses.

NELSON MERRILL.
